Primary Examiner — Janice Hallmark*Assistant Examiner* — Adedoyin Taiwo Odeyale(57) **CLAIM**

I claim the ornamental design for an articulating diffuser, as shown and described.

DESCRIPTION

FIG. 1 is a front perspective view of an articulating diffuser showing my new design;

FIG. 2 is a front elevation view.

FIG. 3 is a rear elevation view.

FIG. 4 is a right side elevation view.

FIG. 5 is a left side elevation view.

FIG. 6 is a top view.

FIG. 7 is a bottom view.

FIG. 8 is bottom perspective view; and,

FIG. 9 is a top perspective view of the articulating diffuser of FIG. 1, shown in an alternate position.

Broken lines illustrate environmental subject matter that forms no part of the claimed design.
